HAIR RINSING PREPARATION

Russell R. Frew, Mercer Island, Wash., assignor,
by mesne assignments, to Golden Glint Company, Inc., Seattle, Wash., a corporation of Washington

No Drawing. Application June 16, 1937,
Serial No. 148,511

4 Claims. (Cl. 167—88)

The invention relates to improvements in hair rinsing preparations adapted for use for such purpose on human hair and has for its primary object the provision of an improved preparation of 5 the character indicated which will preserve the texture of the hair in its natural fineness and luster.

Other objects will appear hereinafter.

The invention consists in the preparation hereinafter described and claimed.

In making up the preparation phthalic acid and potassium acid phthalate are mixed together in various proportions and in some instances furoic acid added thereto. The phthalic acid used is 10 chemically known as either ortho-phthalic or benzene di-carboxylic acid. The potassium acid phthalate employed is known chemically as such and may be more definitely described as the mono potassium salt of the di-basic acid. The furoic acid employed is known chemically as pyromuic acid or furan-carboxylic acid. If desired, either direct or acid coal tar colors, including certain of the certified food colors, may be blended to get the correct shade, and an acid dye assistant such as 15 aluminum lactate may be incorporated.

Desirable proportions and methods of mixing are as follows:

450 grams phthalic acid, 45 grams potassium acid phthalate and 505 grams furoic acid may be 20 thoroughly mixed together in a mechanical mixer and sifter, approximately one gram of this composition, which is colorless, may be used as a single rinse.

725 grams phthalic acid, 20 grams potassium acid phthalate, 175 grams furoic acid, 50 grams aluminum lactate and 30 grams of Tartrazine are used and mixed thoroughly in a mechanical mixer and sifter. Approximately one gram of this solution may be used as a single color rinse.

40 1145 grams furoic acid, 260 grams phthalic acid, 15 grams potassium acid phthalate, 50 grams aluminum lactate and 30 grams Tartrazine are thoroughly mixed together in a mechanical mixer and sifter. Approximately one and one-half 45 grams of this composition are used as a single color rinse.

910 grams phthalic acid, 50 grams aluminum lactate, 25 grams Sunset Yellow FCF, 10 grams Ponceau SX and 5 grams Indigotine are thoroughly mixed in a mechanical mixer and sifter. Approximately one gram of this composition is used as a single color rinse.

45 1410 grams potassium acid phthalate, 50 grams aluminum lactate, 25 grams Sunset Yellow FCF,

10 grams Ponceau SX and 5 grams Indigotine are mixed thoroughly in a mechanical mixer and sifter. Approximately one and one-half grams of this composition are used as a single color rinse.

1425 grams furoic acid, 50 grams aluminum lactate and 25 grams Indigotine are mixed thoroughly in a mechanical mixer and sifter. Approximately one and one-half grams of this composition are used as a single color rinse.

15 The phthalic acid, potassium acid phthalate, 10 and furoic acid employed leave the hair soft and pliable and do not render the same harsh and brittle after a time as do such acids as tartaric and citric acids. This is particularly true when the phthalic acid and potassium acid phthalate are used together. The acid dyes Tartrazine, 20 Sunset Yellow, Ponceau, and Indigotine are all water soluble acid coal tar coloring substances and will be found to be highly efficacious for the purpose.

25 Preferably the composition is mixed in the powder form and packaged for resale as such. However, the preparation may be put up in tablet, cake, paste or concentrated solution, as desired. The requisite quantity of the composition should be dissolved in approximately one quart of warm water and the hair rinsed in the usual manner, either with or without previously shampooing the hair.

30 The ingredients employed are not deliquescent or hygroscopic and, therefore, have no tendency to cake in the package due to temperature changes and humidity. It will be found that the preparation disclosed is very efficient in removing soap curds from the hair and will preserve the texture 35 of the hair in its natural fineness and luster.

35 While I have set forth the preferred embodiments of my invention, these are capable of variation and modification without departing from the spirit of the invention. Therefore, I do not wish 40 to be limited to the precise details disclosed, but desire to avail myself of such variations and modifications as fall within the scope of the appended claims.

I claim:

1. A hair rinse including phthalic acid.
2. A hair rinse including potassium acid phthalate.
3. A hair rinse including furoic acid.
4. A hair rinse including one of the group consisting of phthalic acid; potassium acid phthalate; furoic acid; and water soluble acid coal tar coloring matter.

RUSSELL R. FREW.
